UNITED STATES PATENT OFFICE.

WILLIAM H. HARRINGTON, OF HARTFORD, CONNECTICUT, ASSIGNOR TO THE ARROW ELECTRIC COMPANY, OF HARTFORD, CONNECTICUT, A CORPORATION OF CONNECTICUT.

ELECTRIC SWITCH.

Application filed November 7, 1923. Serial No. 599,499.

To all whom it may concern:

Be it known that I, WILLIAM H. HARRINGTON, a citizen of the United States of America, residing at Hartford, in the county 5 of Hartford and State of Connecticut, have invented certain new and useful Improvements in Electric Switches, of which the following is a specification.

My invention relates to electric switches, 10 and particularly to a switch of the flush type. The object of my invention is to provide a mechanism of such construction that it may be arranged in a very shallow insulating base, and, secondly, that it may be operated by any one of several different types 15 of actuating devices.

Various improvements in detail of construction will be set forth at greater length in the following specification, or shown in 20 the accompanying drawings, in which—

Fig. 1 is a longitudinal section on an enlarged scale, through a push button switch in which my invention is embodied in one form;

Fig. 2 is a horizontal section therethrough;

Fig. 3 is a section on the line 3—3, Fig. 1;

Fig. 4 is an exploded view of the switch mechanism and frame;

Fig. 5 is a longitudinal section illustrating the operation of the switch by means of a lever; and

Fig. 6 is a similar view illustrating its operation by means of a key.

In various installations it is desirable to employ a switch of such construction that it may be mounted in a shallow outlet box, or within molding such as is commonly used in office buildings, factories, etc. It is quite es- 35

sential from a practical standpoint, furthermore, that the depth of the switch body be such with respect to the depth of the outlet box, or equivalent structure, that lead wires may be passed beneath the insulating body of the switch from one end of the box to the other. Considerable clearance be- 45

tween the bottom of the box and the bottom of the switch body must accordingly be afforded. It is also desirable to provide a switch mechanism of such character that it may be utilized interchangeably with several different types of actuating means, such as push buttons, levers, and keys, to meet the preference of the architect, or the cus- 50

tomer, for one or the other of these types. 55 The present invention provides a switch which meets these requirements.

In Figs. 1 to 4 inclusive, I have illustrated the invention in a switch of the push button type, while in Fig. 5 the operation of the 60 mechanism by means of a rocking lever is indicated, and in Fig. 6 its operation by means of a key is shown.

While the construction and arrangement of the parts is subject to considerable variation, that shown is a practical and workmanlike structure which has proved efficient in service.

As illustrated, the body of the switch comprises a shallow cup-shaped member 15 of 70 insulating material, such as porcelain, the over-all depth of which, in the commercial device, is approximately one inch. Its chamber 16 houses the switch contacts and the toggle mechanism. I have shown a single 75 pole switch having two contacts 17 and 18, but it will be recognized by any one skilled in the art that the invention may be applied to a three- or four-point switch without the exercise of more than ordinary skill in ac- 80 cordance with standard practices. Both contacts are integral with offset plates 19 and 20 which overlie depressed ledges 21 and 22 where they are secured by screws 23 piercing the base. The plates also carry binding screws 24 and 25, by which lead wires may be connected.

Within the switch chamber 16, and rising from the floor thereof at opposite ends of the chamber, are formed shoulders 26 and 90 27 pierced at 28 to receive screw bolts 29 by which the frame of the switch mechanism is secured in position. The frame is preferably struck from sheet metal and com- 95 prises a pair of end webs 30 and 31 tapped at 32 to receive the holding screws 29, and united by the arch-like side plates 33—34, the legs of which are integral with and off- set from the opposite side margins of the end webs. Extending downwardly from the adjacent ends of the webs 30 and 31, and lying against the opposed faces of the shoul- 100 ders 26 and 27, are lugs 35 and 36. The webs are also pierced by slots 37 and 38 which register with channels 39 formed in the shoulders. The side plates 33 and 34 of the frame are pierced in register at 40 ad- 105 jacent their upper edges, while rounded

bearing lugs 41 are struck from the lower margins of the crown of the arch and outwardly offset therefrom.

Mounted on the bearing lugs 41 is the 5 yoke 42 which carries the switch bar 43. For a single pole switch of the type shown, the leg 44 of the yoke may be of hook shape to afford an open bearing notch 45 which may be freely engaged with one of the bearing lugs 41 of the frame which the yoke straddles. The other bearing for the yoke is formed in a U-shaped bracket 46, the head of which is slotted at 47 but provided with a cross bar 48 which rests upon the other 10 lug 41 of the frame in the assembled position of the yoke. The arms 49 of the bracket are shouldered, and the reduced ends pass through one leg of the yoke 42 and through the metal and insulating plates 50 and 51, respectively, between which the switch blade 43 is engaged and rigidly clamped by the offset ends of the bracket legs 49. The yoke is also pierced at 52 to receive the lug 53 at the head of the pin 54 upon which is coiled 15 the toggle operating spring 55, the opposite end of which thrusts against the bearing plate 56. Through the hole 57 in the latter the opposite end of the spring guide pin 54 freely passes. The bearing plate 56 is 20 provided with opposite outwardly projecting rounded thrust lugs 58.

These thrust lugs 58 engage in bearing notches 59 at the inner end of the side flanges 60 of the rocker, which are also pierced in register at 61 to receive the bearing pin 62. The latter passes through the holes 40 in the side plates 33 and 34 of the frame, on which the rocker is thus pivoted. The side flanges 60 of the rocker are connected together by integral cross bars 63 and 64 on opposite sides of its axis of oscillation, and from these webs extend, in opposite directions, pairs of downwardly curved bearing fingers 65 and 66, respectively.

When the switch mechanism is operated by push buttons, the latter may be of the type illustrated, comprising insulating heads 67, each having secured thereto, and preferably embedded therein, one end of a 50 flat shank 68. These shanks are adapted to be passed through and freely guided in one or the other of the holes 37 and 38 in the end webs 30 and 31 of the frame. Lateral notches 69 in opposite edges of the shank are of sufficient extent to permit the shank to be freely passed between the bearing fingers 65 or 66 of the rocker which are thus freely and detachably engaged with the shanks, while the rocker and push buttons are constrained to move together. In order to guide the push buttons and insure their rectilinear motion, they are guided in apertures 70 in the switch-carrying yoke 71 through which they pass.

65 The operation of the switch is readily un-

derstood by those skilled in the art. In the position shown in Fig. 1 the switch bar is in circuit-closing position. Upon the depression of the "out" push button 67 the rocker is swung on its axis 62, thus forcing 70 one end of the spring 55 across the axis of oscillation 41 of the switch bar yoke 42. At the same time the spring 55 is further compressed so that its biasing action is increased. As soon as the end of the spring 75 operatively engaged by the rocker is passed across the axis 41 on which the switch bar oscillates, the spring exerts its biasing action in opposite direction and causes the switch bar to move with snap action to the "off" 80 position of the switch. The angular throw of the switch bar is limited by the impingement of the yoke against the downwardly offset lugs 35 and 36 of the switch frame which bear against the shoulders 23 and 27 85 of the insulating body of the casing. The throw of the rocker is also limited by the impingement of the downwardly offset ends of the fingers 65 and 66 against the webs 30 and 31 of the frame which also rest upon 90 these shoulders. It is thus clear that the shocks of impact are taken by the body of the casing at a point at which it is very rugged, and that the switch frame itself is substantially relieved from the strains of 95 impact incident to the snap action of the switch. It will be clear, furthermore, that a long throw of the switch bar is secured—practically the entire depth of the switch 100 chamber, and that a wide break between the switch bar and the contacts is attained, thus enabling the switch to handle relatively heavy current without danger of failure. The rectilinear guidance of the push buttons is a feature of commercial value since 105 the buttons are maintained in exact position, and no sloppy movement is possible.

As above stated, the mechanism lends itself to operation by other means than the push buttons 67. Thus, in Fig. 5 I have shown the rocker oscillated by means of a lever 72 which may be secured upon the yoke 73 in the manner indicated in the co-pending application Ser. No. 538,271, filed 110 February 21, 1922. At the inner end of the lever are bearing lugs 74 and 75 so positioned that they rest upon and operatively engage the webs 63 and 64 of the rocker on opposite sides of its axis of oscillation. Consequently, upon the oscillation of the lever 72, one or the other of the lugs 74, 75, acts upon the rocker to cause it to oscillate, and thus to operate the switch mechanism in the same fashion as that above described in connection with the push button devices.

If it be desired to operate the switch by means of a key, this may be readily accomplished as indicated in Fig. 6. Appropriate key-ways 76 are provided in the face plate 77, and also in the yoke 78, these ways 115 120 125 130

being located above the fingers 65 and 66 respectively of the rocker. It is obvious that upon the insertion of the key 79 through the proper key-way, its inner end 5 bears against the upper end of the rocker and forces it downward, thus operating the switch mechanism in the fashion above described.

To enable the mechanism to be used with 10 any one of the three types of operating devices, it is merely necessary therefore to change the supporting yoke and the face plate to conform to the type of operating device desired. The switch mechanism remains the same in all cases. The economy 15 to the manufacturer or jobber is obvious.

As above stated, the construction is such that the mechanism may be mounted in an extremely shallow insulating body. A commercial switch which will amply take care of and safely break a standard lighting circuit may be arranged in a cup that is only one inch deep over all, thus permitting the switch to be mounted in an outlet box which 20 is one and one-half inch deep. Ample clearance beneath the switch is thus afforded for the lead wires which are carried through beneath the switch from one end of the box to the other. The stroke of the push buttons, when used, is but one-quarter inch, and they are guided as above stated so that they are always at right angle to the face plate 25 of the switch. The structural parts are all rugged and are readily manufactured and assembled.

Premising that the foregoing specification and the drawings set forth only a specific illustrative embodiment of my invention, which may be variously modified, I claim—

40 1. In a toggle switch mechanism, an oscillating switch member, an oscillating rock lever, a switch spring operatively interposed between said rock lever and switch member, and shiftable at one end by the rock lever from one side to the other side of the axis 45 of oscillation of the switch member, said rock lever being shaped for interchangeable operating slidable engagement by actuating members of different types.

50 2. In a toggle switch mechanism, an oscillating switch member, an oscillating rock lever, a switch spring operatively interposed between said rock lever and switch member, and shiftable at one end by the rock lever from one side to the other side of the axis 55 of oscillation of the switch member, said rock lever being shaped on opposite sides of its rocking axis for interchangeable operating engagement by actuating members of different types.

60 3. In a toggle switch mechanism, an oscillating switch member, an oscillating rock lever, a switch spring operatively interposed between said rock lever and switch member, and shiftable at one end by the rock lever

from one side to the other side of the axis of oscillation of the switch member, said rock lever being shaped at different points on opposite sides of its rocking axis for interchangeable operating engagement by actuating members of different types.

4. In a toggle switch mechanism, an oscillating switch member, an oscillating rock lever, a switch spring operatively interposed between said rock lever and switch member, and shiftable at one end by the rock lever from one side to the other side of the axis of oscillation of the switch member, said rock lever being shaped for interchangeable operating slidable engagement by actuating members of different types.

5. In a toggle switch mechanism, an oscillating switch member, an oscillating rock lever, a switch spring operatively interposed between said rock lever and switch member, and shiftable at one end by the rock lever from one side to the other side of the axis of oscillation of the switch member, in combination with a pivoted actuating lever having means adapted for sliding operative engagement with the rock lever on opposite sides of the latter's axis.

6. In a toggle switch mechanism, an oscillating switch member, an oscillating rock lever, a switch spring operatively interposed between said rock lever and switch member, and shiftable at one end by the rock lever from one side to the other side of the axis of oscillation of the switch member, in combination with a pivoted actuating lever having legs straddling the axis of the rock lever and adapted for sliding operative engagement with the rock lever.

7. In a toggle switch mechanism, a rock lever having on opposite sides of its axis longitudinally slotted bearing arms adapted for sliding engagement with either the legs of an actuating lever or the shanks of push buttons.

8. In a toggle switch mechanism, a rock lever having a lug extending in a direction substantially at right angles to the rocking axis, and bearing surfaces on opposite sides of said axis extending in a direction substantially at right angles to said lug, said bearing surfaces being shaped to afford sliding engagement with cooperating actuating devices of different types.

9. In a toggle switch mechanism, a rock lever having a lug extending in a direction substantially at right angles to the rocking axis, and bearing surfaces on opposite sides of said axis extending in a direction substantially at right angles to said lug, said bearing surfaces having offset portions in extension thereof to form stops limiting the throw of the lever.

10. In a toggle switch mechanism, a rock lever having a pair of spaced legs united on opposite sides of its rocking axis by solid

- 4
- webs affording bearing surfaces for sliding engagement with a rock lever, said webs being extended in opposite directions by pairs of spaced fingers, each pair of fingers being 5 adapted to receive between said fingers the shank of an actuating push button.
11. In an electric switch, a rock lever, an oscillating switch member, spaced abutments having opposed faces between which the 10 switch member rocks, and by which its throw is limited, said abutments having faces lying at an angle to said opposed faces and engaged by the rock lever to limit its throw.
12. In an electric switch, an insulating 15 base of cup shape, integral shoulders rising from the bottom of the cup at the opposite ends of the chamber afforded thereby, a switch member oscillating between said shoulders and having its throw limited 20 thereby, and a rock lever, the ends of which overlie said shoulders and impinge against the upper faces thereof to limit its throw.
13. In an electric switch, an insulating 25 base of cup shape, integral shoulders rising from the bottom of the cup at the opposite ends of the chamber afforded thereby, a switch frame having end webs resting on said shoulders and offset elements lying against the opposed faces of said shoulders.
14. In an electric switch, an insulating 30 base of cup shape, integral shoulders rising from the bottom of the cup at the opposite ends of the chamber afforded thereby, a switch frame having end webs resting on 35 said shoulders and offset elements lying against the opposed faces of said shoulders, together with a switch member pivoted on the frame and oscillating between said shoulders and impinging against said offset 40 portions of the frame to limit its throw.
15. In an electric switch, a cup-shaped insulating body having integral shoulders rising from the bottom of the cup at the 45 opposite ends of the chamber afforded thereby, a switch frame having webs resting on said shoulders, a rocker pivoted on the frame and having a throw limited by impingement against said webs.
16. In an electric switch, a cup-shaped insulating body having integral shoulders rising from the bottom of the cup at the opposite ends of the chamber afforded thereby, a switch frame having webs resting on said shoulders, a rocker pivoted on the frame 55 and having a throw limited by impingement against said web, together with actuating means having a sliding engagement with said rocker on opposite sides of its rocking axis.
17. In an electric switch, a cup-shaped insulating body having integral shoulders rising from the bottom of the cup at the opposite ends of the chamber afforded there- 60 by, a switch frame having webs resting on said shoulders, a rocker pivoted on the frame 65 and having its ends offset to form stops impinging against said webs to limit the throw of the rocker, together with actuating means having a sliding engagement with said rocker at points between said offset 70 ends, but on opposite sides of its rocking axis.
18. In an electric switch, a cup-shaped insulating body having integral shoulders rising from the bottom of the cup at the opposite ends of the chamber afforded thereby, 75 a switch frame having webs resting on said shoulders, said webs and shoulders being recessed to accommodate an actuating member.
19. In an electric switch, a cup-shaped insulating body having integral shoulders rising from the bottom of the cup at the opposite ends of the chamber afforded thereby, a switch frame having webs resting on 80 said shoulders, upstanding side plates extending between and integral with said end webs, downwardly extending members offset from said webs, a switch member pivoted on said side plates and having an arc of oscillation limited by said downwardly extending members, and a rocker pivotally supported on said side plates and having 85 its throw limited by said webs.
20. In an electric switch, a toggle mechanism comprising a rocker having spaced 90 side flanges united by cross webs, said flanges having portions upstanding above said cross webs and by which said rocker is pivotally supported, the portions of said flanges below said webs being shaped for 95 operating connection with an associated switch element.
21. In an electric switch, a toggle mechanism comprising a rocker having spaced 100 side flanges united by cross webs, said flanges having portions upstanding above and between said cross webs and by which 105 said rocker is pivotally supported, the portions of said flanges below said webs being shaped for 110 operating connection with an associated switch element.
22. In an electric switch, a toggle mechanism comprising a rocker having spaced 115 side flanges united by cross webs, said flanges having portions upstanding above said cross webs and by which said rocker is pivotally supported, the portions of said flanges below said webs being shaped for 120 operating connection with an associated switch element, said webs having oppositely extending portions adapted for sliding engagement by rocker actuating means.

In testimony whereof I have signed my name to this specification.

WILLIAM H. HARRINGTON.
